UNITED STATES PATENT OFFICE.

ISAAC A. GIBBS, OF ROANOKE, VIRGINIA, ASSIGNOR OF ONE-HALF TO JOHN ROSE, OF ROANOKE, VIRGINIA.

TRACK-SANDING APPARATUS.

No. 920,863.

Specification of Letters Patent.

Patented May 4, 1909.

Application filed April 29, 1908. Serial No. 430,007.

To all whom it may concern:

Be it known that I, ISAAC A. GIBBS, a citizen of the United States, residing at Roanoke, in the county of Roanoke and State of Virginia, have invented certain new and useful Improvements in Track-Sanding Apparatus; and I do hereby declare the following to be a full, clear, and exact description of the invention, such as will enable others skilled in the art to which it appertains to make and use the same.

My invention relates to certain new and useful improvements in track-sanding apparatus for locomotives.

It has for its object to provide an apparatus which shall be effective at all times and free from the liability usually experienced of the choking of the sand delivery pipe or conduit, owing to the jamming therein of the sand which occurs by reason of the same when moist, accumulating at any locality within said pipe.

In the latest and most improved sanding apparatus, the sand as it flows from the sand dome is injected into the delivery pipe or conduit over a partition, in the sand trap by a blast of air from a nozzle located within and near the bottom of the sand trap, and after passing up and over the partition referred to, it falls by gravity through the vertical delivery pipe or conduit to the rail. In this construction the force of the air blast is exhausted in lifting the sand over the partition of the sand trap and the falling sand is liable to, and frequently accumulates at various localities in the delivery pipe to such an extent as to constitute an obstruction or positive dam to the flow of the same, necessitating its dislodgment by blows upon the delivery pipe, thus defacing and ultimately damaging the same.

My invention is designed to overcome these difficulties and consists in providing an apparatus of the type referred to with an auxiliary air blast leading directly into the upper end of the vertical delivery pipe or conduit, and adapted by its application to free said pipe or conduit of any obstructions therein as will be hereinafter and in detail explained.

In order that those skilled in the art to which my invention appertains may know how to make and use my invention and appreciate its advantages I will proceed to describe the construction and operation of the

same referring to the accompanying drawing in which—

Figure 1 is a perspective view showing a sand dome with my improved apparatus connected therewith; Fig. 2 is a detail plan view. Fig. 3 is a side elevation, and Fig. 4 is a detail view showing modification as to blast-pipe entrance.

Similar reference numerals indicate like parts in the several figures of the drawing.

1, represents an ordinary locomotive sand dome to which is secured a sand trap 2, by means of screw bolts 3, in an ordinary manner.

The sand trap communicates at 4, with the sand dome and is formed with a sand passage 5, extending upwardly in an inclined direction and then downward and communicating with the vertical delivery pipe or conduit 6, connected therewith by a screw coupling 7.

The usual air nozzle 8, is located within the sand trap and is connected in any desired manner with a pipe 9, leading from the compressed air reservoir, and when compressed air is admitted a supply of sand is projected by the blast through the nozzle 8, to the sand passage 5, and then delivered into the vertical pipe or conduit 6, in an obvious manner and falls by gravity to the track.

10, is an auxiliary air passage through the trap casting and leading directly into the upper end of the vertical delivery pipe or conduit, and this passage is connected by suitable valve controlled pipe connections 11, with the main compressed air reservoir, in order that when necessary a blast of air may be delivered in a vertical direction through the sand delivery pipe or conduit 6, to effect the dislodgment of any sand which may have accumulated for any reason therein, and thus clear said pipe or conduit and enable the sand projected by the primary blast from the nozzle 8, to freely flow to the track.

It will be seen that the air nozzle 8, located at one side of the bridge in the sand trap drives the sand up and over said bridge when, under ordinary circumstances it will travel by gravity through the conduit pipe 6, to the track, but if for any reason the conduit becomes clogged and the sand fails to flow vertically therethrough a blast of air admitted to the sand trap on the opposite side of the bridge therein, and in a vertical direction, constitutes a projectile force and removes any obstruction in the conduit. This auxil-

iary blast not only effects a perfect clearance of any obstruction, but serves also to render the interior surface of the delivery pipe or conduit dry, prevents any oxidation of the 5 same which conduces to the formation of sand obstructions, and renders it unnecessary to resort to the usual practice of striking the conduit with a hammer to dislodge obstructions.

- 10 I have not shown any of the valve mechanism for controlling the supply of air to the air passages as such devices are well understood by those familiar with such devices. I have shown at Figs. 2 and 4, the auxiliary 15 air passage entering from different directions to indicate that I do not wish to be limited in this respect, so long as the compressed air is delivered within the upper end of the vertical sand pipe or conduit in such manner as 20 to follow the vertical path of the sand and to act as means for removing any obstructions within said pipe or conduit, and many changes may be made in other details of construction without departing from the spirit of my 25 invention which resides as stated in the broad idea of combining with a sand delivery apparatus any preferred means for applying a vertically directed blast of air at the upper end of the sand delivery pipe or conduit.
- 30 I am aware that it is not new to admit a blast of air at the upper end of the sand conduit as a means of creating an exhaust which operates to draw the sand from the sand

*dome into the conduit, and that it is not new 35 to apply primary and auxiliary air blasts at one side of the bridge of a sand trap for the purpose of carrying the sand over said bridge, but in neither of these instances is there a blast employed to deliver the sand to the 40 vertical conduit, and a secondary blast delivered in a vertical direction for the sole purpose of removing obstructions which may occur in the conduit.

Having described the construction and 45 advantages of my improved track-sanding apparatus, what I claim as new and desire to secure by Letters Patent is:

In a track sanding apparatus embodying a sand trap in connection with a sand dome, 50 said trap provided with a sand bridge and communicating with a delivery conduit, means for directing compressed air to the sand trap between the sand dome and the bridge in the sand trap, and means for delivering compressed air on the opposite side 55 of said bridge and directly into the upper end of the vertical delivery conduit, substantially as and for the purpose set forth.

In testimony whereof, I have signed my 60 name to this specification in the presence of two subscribing witnesses.

ISAAC A. GIBBS.
